EMERSON B. CAMPBELL, OF BAKERSFIELD, CALIFORNIA.

COVERING FOR ROOFS AND THE LIKE.

No. 842,079.

Specification of Letters Patent.

Patented Jan. 22, 1907.

Application filed May 18, 1906. Serial No. 317,554.

To all whom it may concern:

Be it known that I, EMERSON B. CAMPBELL, a citizen of the United States, residing at Bakersfield, in the county of Kern and State of California, have invented certain new and useful Improvements in Coverings for Roofs and the Like, of which the following is a specification.

The object of the present invention is to provide a cheap, yet effective, waterproof covering for roofs, pipes, the junctures of lean-to buildings, the under sides of bridges, wharves, or the like.

In the accompanying drawing, the figure 15 is a plan view of the invention applied to a roof, successive layers being removed to disclose the structure.

In making my improved roofing I secure by tacks 1 coarse burlap or jute fabric 2 to 20 the roof-boards 3 or to the bridge or other object which it is desired to cover, just sufficient to hold the burlap in place in the preliminary stage and not permanently. I then coat this with a paint 4, either hot or cold, 25 composed of asphaltum and green neutral mineral oils, such as are distilled from crude oil at a temperature not lower than 600° Fahrenheit, and are therefore comparatively non-volatile. The proportions of the above ingredients may vary considerably; but an 30 average proportion would be eighty per centum of the asphaltum and twenty per centum of the oils. This composition possesses an adhesive property, and not only fills the 35 meshes of the burlap, but firmly cements it to the timber. I next lay on another covering 5 of burlap and coat it with paint 6 in like manner as before, and I then cover it with a thin coat of sand 7. I then lay on another 40 coat 8 of the paint and then a coat 9 of the sand, according to the thickness or quality of the work desired.

My invention of improved roofing differs from prior roofings or other water-tight coverings in this respect, that the burlap is cemented directly to the roof or other structure. In prior roofings paper, cloth, and other material have been covered with waterproof paint; but the means for fastening 45 them down permanently to the roof has been not the paint itself, but tacks or nails. It is to be understood that I only use tacks to hold the burlap in place while cementing it to the roof and the tacks are not relied upon as a 50 permanent means of attachment. This is accomplished by means of the cementitious

paint. The advantage of this is that the roofing is not so liable to crack, nor can moisture effect it, as in prior constructions. Where the roofing is nailed onto the boards, 60 air can enter between the boards and the roofing, producing in time a destructive chemical action on the latter and, furthermore, by reason of wind-pressure through the knots and cracks in the boards, causing frequent vibration of the roofing, which is very destructive to it. All this is avoided by my construction of having the roofing cemented down to the boards, and the burlap being a loosely-woven cloth can expand or contract readily without breaking where it 65 covers the spaces between the boards.

The material may also be used to close cracks or openings in overhead bridges or 70 wharves or like structures where there is pedestrian traffic below, preventing any falling of dirt. It is also useful in attaching water-conduits and roofs to the sides of buildings, the burlap being arranged to cover the junction somewhat after the manner of tin coping, 75 and thus displacing said coping, with consequent economy, as well as being more durable. It can also be used to cover piping, especially when submerged in salt water or placed underground. The pipe is first wrapped with 80 burlap and then coated with the paint until a 85 waterproof covering is formed.

I am aware that it has been proposed to secure a fabric direct to a metallic roof by painting said roof and allowing it to dry, also painting the under side of the fabric as it is laid down, and immediately applying the fabric to the roof, so that the freshly-painted surface adheres thereto. My invention differs from this in that the fabric is laid in position upon 90 the roof or other surface first, before any paint is applied thereto, and after a convenient extent of surface has thus been covered the cementitious paint is applied to the upper side of the fabric. This method of covering a 95 surface requires, however, that the fabric shall be a coarse open-meshed one, so that the paint applied on the upper side thereof can pass through the meshes of the interstices of the fabric and secure it directly to the roof 100 and other surfaces. The advantage of this method of covering the roof is its cheapness of application, as the whole roof, or a convenient portion thereof, can be first covered with the fabric and then the paint applied on 105 the upper surface thereof, all of which can be accomplished very quickly. Therefore I do 110

not claim, broadly, a fabric cemented direct to a roof or other surface; but

What I claim is—

1. A waterproof covering for roofs or other structures comprising, as an exclusive base or foundation, a coarse, open-meshed fabric, and a cementitious paint on the upper side and in the meshes of the fabric, cementing the fabric directly to the roof or other structure to be covered, substantially as described.
2. A waterproof covering for roofs or other structures comprising, as an exclusive base or foundation, a coarse, open-meshed fabric, a

cementitious paint on the upper side and in the meshes of the fabric, cementing the fabric directly to the roof or other structure to be covered, and a thin coating of sand on said paint, substantially as described.

In testimony whereof I have hereunto set my hand in the presence of two subscribing witnesses.

EMERSON B. CAMPBELL.
